Accord
J. S. L. of New Jersey
Letter Patent No. 1111-Dated May 1, 1861
Design for a book Stand

The schedule referred to in this letter stands in the part of the

full form it may contain.

It is believed that we, John Harting, Jacob Bawley and John Currie, of the firm of Harting, Bawley & Currie, of the City of Philadelphia, in the State of Pennsylvania, have invented or produced a new and original design for a Stand with an elevated base, of which the following is a full, clear and exact description, reference being had to the accompanying drawings, being a part of this specification, and to the letter of reference marked therewith.

The front plate A of the stand has an ornamental base or pedestal of four curved legs a, a, a, a and a raised panel a. Each of the said legs has a raised panel, ornamented with an ornamental figure as shown in the drawing. The raised panel is of a circular or slightly oval ornament as shown in the drawing.

The front plate B of the stand has two ornamental figures b, b and between them are two doors c, c and a raised ornamental side front d as shown in the drawing.

What we claim as our invention, and to secure by Letter Patent. The design for a stand with an elevated base herein shown and described.
